EXHIBITING DEVICE.

1,113,786.

Specification of Letters Patent. Patented Oct. 13, 1914.

Application filed March 1, 1911. Serial No. 611,623.

To all whom it may concern:

Be it known that I, RUBEN P. JARVIS, a citizen of the United States, and a resident of Smith Center, in the county of Smith 5 and State of Kansas, have invented a new and Improved Exhibiting Device, of which the following is a full, clear, and exact description.

My invention is an exhibiting device, and 10 it comprises a sign board or plate having a row of illuminating devices along its top and bottom, and bearing on its front face the things to be exhibited. These things may of course be letters or pictures, or any 15 form of representation which is useful for the advertiser's purpose.

Reference is to be had to the accompanying drawings forming a part of this specification, in which the same characters of 20 reference indicate the same parts in all the views.

Figure 1 is a front view of my improved exhibiting device partly broken away at the 25 top to show the arrangement of lamps behind the shield or hood; Fig. 2 is a vertical transverse section of my improved sign plate; Fig. 3 is a vertical sectional view taken through the center of one of the reflector shields, and showing the manner in 30 which the light is directed thereby against the face of the sign plate; Fig. 4 is a top view of two adjacent illuminating devices, each in operative relation to its combined shield and reflector; Fig. 5 is a front view 35 of the structure illustrated on Fig. 4, and Fig. 6 is an enlarged sectional view showing the roughened and mirrored rear surface of one of the objects to be exhibited carried by the sign plate.

On the drawings, the sign plate of my 40 improved exhibiting device is indicated by the numeral 1, and the top and bottom edges of this sign plate are over-turned to form hoods 2 and 2'. These hoods have 45 sides 3 and 3' which are partly bent in toward the face of the plate 1, as shown at 4 and 4'. The sign plate 1 should be of metal, so that the top and bottom edges can be 50 bent into the form of hoods shaped as above described, but it is obvious that I may use another material in making the sign plate 1.

The upper row of lamps is indicated by the numeral 6, and the lower row of lamps

by the numeral 6'. These lamps are supported by the upper and lower edge of the 55 sign plate or the bent-over top and bottom of the sign plate, and the in-turned sides of the hoods assist in directing the rays of light against the face of the sign plate. On this face are secured, for example by cement 5^a, 60 the characters or other objects to be exhibited, which, in the form shown on the drawings, are letters, indicated by the numeral 5. These letters are made of transparent and preferably highly refractive glass, and the 65 back of each letter is ground with carbondum powder or other suitable substance. The back of each letter is first ground with fine powder and then several more times with powder that is successively coarser. 70 This forms a rough or granular mirrored surface on the back of each letter, and this surface is mirrored by coating it with mercury or other highly reflective substance, care being taken to fill thoroughly each little interstice or pitting formed during the process of grinding. In consequence, light passing through the front of each of the glass letters from whatever angle is refracted and reflected, and re-refracted from the back there- 75 of and diffused practically in all directions.

The illuminating devices are shown as being formed of incandescent electric lamps, and I combine the same by using red, yellow, 80 blue and white globes, arranged in the order named, from one end of the sign to the other, each of these rows of colored 85 lamps being separately connected to a circuit closer or flasher. Each incandescent bulb is provided with a combined shield and reflector, indicated as a whole by the numeral 7, which prevents each lamp from interfering with the rays of a different color emitted by its immediate neighbor, and at the same time causes the rays of multi-colored light to fall upon the letters 5 in a proper manner. To this end each of the reflector shields is formed with a closed back and open front, the adjacent sides of each pair of shields extending to a sufficient 90 distance between the illuminating devices partly inclosed thereby. The lamps are indicated by the distinctive letters w, r, y, b. White, red, yellow and blue globes are all 95 that are necessary to produce all the desirable colors by differently combining them.

However, I may use any combination of colored globe, such as green, violet and orange red.

Each reflector shield consists of a bottom 5 which slopes outward and downward, as shown at 9, and terminates in upright sides 8. These sides flare outward near the top, as shown by the numeral 9', and the sides 8 with their flared top portions 9' are curved 10 around the illuminating devices, as shown at 10, so as to form a continuous reflecting surface at the rear of the illuminating devices. The rays of light emanating from each of the illuminating devices are all reflected upward, some from the flaring top 15 10, and some from the bottom 9 and sides 8, and the in-turned sides of the hoods 2 and 2' assist the reflector shield 7, to cause all of the light to fall upon the face of the sign 20 plate and illuminate the letters or other characters thereon. At the same time the rays of light emanating from one illuminating device cannot be refracted or reflected by a different colored globe adjacent the 25 same. The above is the preferable form of reflector used, although I may use other reflectors for preventing interference of one colored lamp by a different colored lamp.

When all the illuminating devices are 30 turned on, the rays of different colors striking the granular backs of the letters are diffused in every direction, and the light appears white to the eye of the observer. This is because the colors employed are blended 35 in their proper proportions by the reflecting surfaces formed on the backs of the letters in the manner above described. A sign constructed in this way can be used in the day time without illumination, and at night, 40 when the electric energy is turned on, the letters are discernible at a very acute angle, because nearly all of the light emitted by the illuminating devices is utilized.

As stated above, I connect all the different 45 colored lamps separately to a flasher, and I can arrange to illuminate them either separately or together. For example, I can keep all the lamps permanently illuminated, or I can cause all of them to flash at regular 50 intervals. I can also turn on one color and then another, in order to attract attention to the sign; or I can flash two colors at one

time, the rays of light being blended and mixed after being thrown from the sign upon the eye of the observer. I may also 55 cause the lamps to illuminate in succession, passing from one end of the sign to the other, by connecting each light separately to the flasher; or I may flash one color at the top and another color at the bottom, or a 60 combination of two colors at the top and a different combination of two colors at the bottom. When different colors are flashed in this way the light need not be strong, as the contrast intensifies, and thus considerable 65 economy in the consumption of electric current can be obtained. In fact, different colors can be combined in a great variety of ways in addition to the few mentioned above, according to the choice or convenience 70 of the user. I can of course change the letters on the sign and replace them by other letters to form almost any word or sentence, and I may attach to the face of the sign plate to be illuminated, things other than 75 letters, such as figures or pictures.

Having thus described my invention, I claim as new and desire to secure by Letters Patent:

An exhibiting device comprising a sign 80 plate having means for forming a hood located along an edge of the same, a plurality of illuminating lamps arranged in groups, the members of each group being adapted to emit light of different colors, said lamps being supported in position to be covered by said hood, means adjacent each individual lamp for throwing the light emitted thereby upon the face of the sign plate, and for preventing the rays of light emitted by one 85 lamp from reflecting from a lamp adjacent thereto, said last-named means being open at the top and the side adjacent the sign plate and being arranged to inclose each lamp except on top and on the side adjacent 90 the sign plate, and objects carried upon the face of the sign plate to be exhibited.

In testimony whereof I have signed my name to this specification in the presence of two subscribing witnesses.

RUBEN PALMER JARVIS.
